HUNTING KNIFE SHEATH

Theodore G. Schrade, Nichols, Conn., assignor to
George Schrade Knife Company, Inc., Bridge-
port, Conn., a corporation of Connecticut

Application May 15, 1952, Serial No. 19,723

Term of patent 3½ years

(Cl. D22—6)

To all whom it may concern:

Be it known that I, Theodore G. Schrade, a citizen of the United States and resident of Nichols, Connecticut, have invented a new, original, and ornamental Design for Hunting Knife Sheath, of which the following is a specification, reference being had to the accompanying drawings, forming part thereof.

In the drawings:

Fig. 1 is a front elevation of the hunting knife sheath, showing my new design;

Fig. 2 is a side elevation; and

Fig. 3 is a sectional view taken along the line 3—3 of Fig. 1.

I claim:

The ornamental design for a hunting knife sheath, substantially as shown.

THEODORE G. SCHRADE.
